United States Patent Office

Des. 193,032
Patented June 12, 1962

193,032

BOTTLE

Felix V. Waser, Detroit, Mich., assignor to Feigenson, Inc., Detroit, Mich., a corporation of Michigan

Filed Apr. 10, 1961, Ser. No. 64,686

Term of patent 14 years

(Cl. D58—8)

The FIGURE is an elevation of a bottle embodying my new design;

The bottle is symmetrical about its vertical center line.

I claim:

The ornamental design for a bottle, substantially as shown and described.
